Francis H. Hill

FRANCIS H. HILL, OF CHICAGO, ILLINOIS.

Letters Patent No. 83,964, dated November 10, 1868.

IMPROVED COFFIN.

The Schedule referred to in these Letters Patent and making part of the same.

To all whom it may concern:

Be it known that I, FRANCIS H. HILL, of Chicago, in the county of Cook, and State of Illinois, have invented a new and useful Improvement in Coffins; and I do hereby declare and make known that the following is a full, clear, and exact description of the same, reference being had to the accompanying drawings, and the letters and figures marked thereon, which form part of this specification.

My said invention relates to the manner of arranging the face-glass of coffins, and it consists in having a separate movable frame for the glass, which is so constructed and arranged in the opening in the top of the coffin in which it fits, that it may be depressed and moved back in a suitable slide or groove beneath the lid of the coffin, so as to open the coffin; or, said frame for the glass can be opened upward, as upon a hinge, for the same purpose, thus enabling the coffin to be opened at the head to give access to the face of the corpse, without removing the glass from the opening or frame in which it is set.

To enable those skilled in the art to understand how to construct and use my said invention, I will proceed to describe the same with particularity, making reference in so doing to the aforesaid drawings, in which—

Figure 1 represents a plain or top view of my invention;

Figure 2 is a central longitudinal vertical section thereof;

Figure 3 is a bottom view of the lid, with its attachments; and

Figure 4 is a detached view of frame containing the glass.

Similar letters of reference in the several figures denote the same parts of my said invention.

A represents the top or lid of the coffin, having an opening of suitable shape therein, near the head, into which a movable frame, B, is closely fitted, containing a glass, B', as shown.

The said frame B is provided upon each side, at the lower end, with short pins or lugs, marked d d, and near the middle of each side with two similar lugs or pins, marked d' d', as shown in fig. 4.

In the sides of the opening in the lid A, which receives the frame B, are slots, f f, as shown in fig. 1, to receive said lugs d' d', which slots or grooves curve, as shown in fig. 2, and connect with the grooves c parallel with the lid, and beneath the same, said grooves being cut or formed in the inner faces of the bars D D, secured to the under side of the lid, as shown in fig. 2.

E E represent two springs, secured at one end properly to the lid, or to blocks F, attached thereto; the other ends of said springs lying beneath the frame B, and supporting the same as shown, and as hereinafter described.

O represents a bar, arranged beneath the lid at the head, upon which the end of the frame B is supported when adjusted in the aperture in the lid, so as to close the coffin, as shown in fig. 2.

A screw or pin, b, is provided with a horizontal lip, b', which can be turned into a recess in the end of the frame B, to lock it firmly in place, but can be turned back to unlock the said frame when it is desired to open the same upwards.

In the side-bars D D, containing the aforesaid grooves c c, at the heel of the frame B, there are vertical slots, c' c', opening up from said grooves c c, as shown in fig. 2.

The rear lugs d d lie in said vertical grooves, c' c', and the central lugs d' d' in the vertical grooves f f, when the frame B is adjusted in place, as shown in figs. 1 and 2, the springs E E holding said frame up in position.

When it is desired to open the aperture in the coffin-lid, the rear end of the frame is depressed until the lugs d d move down into the grooves c c, when said frame may be moved back beneath the lid, the lugs d d sliding in the grooves c c, and the lugs d' d' passing down the curve of f f into the said grooves c c, as clearly shown in fig. 2, the springs E E yielding to permit such adjustment.

When the aperture is closed the frame B is moved forward, until the lugs d and d' come to the grooves c and f, when the springs E E throw the frame up into place, and the lock b b' is turned to secure the same as desired.

The said removable frame, if desired, can be unlocked and opened upward, as indicated by the dotted lines in fig. 2, turning upon the lugs d d as upon a hinge.

When this mode of opening the frame is employed, any other species of hinge may be used, and the provisions for permitting the sliding of the frame may be omitted, and also the springs E E may be dispensed with. In such case, the lugs d' d' upon the frame B are of no practical necessity. Or the construction and arrangement of the frame and its attachments may be such, that the frame may be moved back beneath the lid, and opened upwards, as described and shown. Or it may have such construction as will enable the frame to slide back under the lid only, and have no movement upward upon a hinge.

A' represents a movable cover, pivoted to the lid at a', so that it may be turned or moved around from the position indicated in the drawings, over the glass and its frame, to cover and protect the same.

When the frame B is removed from the opening, by sliding the same back beneath the lid, or when it is moved forward to close said opening, the lock b' need not be disturbed or moved, this being necessary only when the frame B is opened upward.

Having described the nature, construction, and op-

eration of my invention, I will specify what I claim, and desire to secure by Letters Patent.

1. I claim so connecting and arranging a movable glass frame, B, in a coffin-lid, that the same may be depressed and moved down beneath the lid, and restored to place again, substantially as herein described.

2. I claim so hinging or connecting said movable frame B with and in the coffin-lid, that the same may be opened upwards and closed again, substantially as specified and set forth.

3. I claim so connecting and arranging the movable frame B with and in the coffin-lid, that it may be moved back beneath the lid, or opened upwards, substantially as and for the purposes shown and described.

FRANCIS H. HILL.
